PULL TAB FOR A TEAR STRIP OPENER

Ralph C. Van Kuren, Coopersburg, and Louis S. Schwartz,
Schnecksburg, Pa., and Raymond O. Palmgren, Glen-
view, Ill., assignors to Bethlehem Steel Corporation

Filed Aug. 18, 1965, Ser. No. 86,620

Term of patent 14 years

(Cl. D58—26)

Fig. 1

Fig. 2

Fig. 3

Fig. 4

Fig. 5

FIGURE 1 is a perspective view of a pull tab for a tear strip opener showing our new design, with a tear strip and can end being shown fragmentarily in broken lines for illustrative purposes only.

FIGURE 2 is an enlarged scale top plan view of the tab.

FIGURE 3 is a left side elevational view.

FIGURE 4 is a front elevational view.

FIGURE 5 is a right side elevational view.

We claim:

The ornamental design for a pull tab for a tear strip opener, as shown and described.
